R. V. LEAF.
DIRECTION INDICATOR.
APPLICATION FILED SEPT. 9, 1920.

1,372,967.

Patented Mar. 29, 1921.

UNITED STATES PATENT OFFICE.

ROY V. LEAF, OF LOUISVILLE, KENTUCKY.

DIRECTION-INDICATOR.

1,372,967.

Specification of Letters Patent. Patented Mar. 29, 1921.

Application filed September 9, 1920. Serial No. 409,165.

To all whom it may concern:

Be it known that I, ROY V. LEAF, a citizen of the United States of America, residing at Louisville, in the county of Jefferson 5 and State of Kentucky, have invented certain new and useful Improvements in Direction-Indicators, of which the following is a specification.

This invention relates to signals and has 10 special reference to a signal for automobiles arranged to afford visual indication of the direction in which an automobile is about to turn and also to afford indication that such vehicle is about to stop.

One important object of the invention is 15 to provide an improved general construction for devices of this character.

A second important object of the invention 20 is to provide a simple and improved form of lamp support for devices of this character.

A third important object of the invention 25 is to provide a lamp support and casing of improved character wherein the lamp supporting frame, when surrounded by the casing, will divide the latter into compartments so as to preclude the light from a particular lamp entering a compartment other than the one which it is desired to illuminate and 30 thus prevent false or misunderstood signals.

With the above and other objects in view, as will be hereinafter apparent, the invention 35 consists in general of certain novel features of construction and arrangements of details hereinafter fully described, illustrated in the accompanying drawings and specifically claimed.

In the accompanying drawings like characters of reference indicate like parts in the 40 several views, and—

Figure 1 is a perspective view of the complete device.

Fig. 2 is a rear view of the lamp casing with the rear wall or closure removed.

Fig. 3 is a section on the line 3—3 of Fig. 1.

Fig. 4 is a perspective view of the lamp supporting frame or bracket removed from the casing.

In the embodiment of the invention herein illustrated it will be seen that the device consists of two distinct but co-operating parts, viz., the lamp casing and its contents and the circuit closer, the former being lo-

cated at the rear of the automobile so that it 55 may be seen by a following vehicle and the latter being located preferably on the instrument board so that it may be manipulated by the driver of the automobile.

The first part is preferably formed with 60 a casing body 10 having front, top, bottom and end walls but open toward the rear, this rear opening being closed by a cover 11 held on the casing body 10 by screws 12. This casing body is secured to a bracket 13 65 provided with slots 14 so that, by means of ordinary bolts and nuts the casing may be mounted on the usual license number bracket customarily provided on the rear of automobiles.

The lamp supporting bracket is formed 70 from three strips of sheet metal, each strip being as wide as the casing is deep from front to rear. The upper and lower strips are formed alike but reversely positioned. 75 Each of these strips consists of a straight body portion 15 having respective end portions 16 and 17 bent at right angles to the body portions, these right angular portions are bent upward in the case of the upper 80 strip and downward in the case of the lower strip, being each equal in length to about one third the distance between the top and bottom walls of the casing. Extending parallel to each body portion from the respective end 85 16 is a terminal portion 18, this terminal portion with the body portion added thereto being equal in length to the distance between the end walls of the casing. The terminal portions are secured respectively to 90 the top and bottom of the casing by bolts 19 and the portions 17 are secured to one end wall by bolts 20. The casing is by this means divided into three compartments, a central compartment in the shape of the letter T with its stem horizontal, and upper and lower rectangular parallelopipedal compartments.

The central compartment is divided into two parts by the third strip of metal which 100 consists of a central portion 21 and end flanges 22 which are secured by bolts 23 to the body portions 15 of the other strips.

On the portion 16 of the upper strip, the portion 21 of the middle strip and the portion 17 of the bottom strip are fixed lamp sockets 24 carrying lamps 25 and on the front wall is secured, in the head of the T-

shaped compartment, a socket 26 carrying a lamp 27, a housing 28 closed rearwardly with red glass 29 being provided on the closure or cover 11 for a permanent 5 rear light. Furthermore the closure is provided opposite the right hand portion or stem of the T-shaped compartment, with stencil like cut out letters 30 forming the word "Stop" while there is also cut out of 10 the casing, opposite the upper and lower compartments, arrows 31, the upper arrow pointing to the left and the lower to the right as shown.

From the lamp sockets wires 32 lead 15 through a conduit 33 to circuit closer buttons marked respectively L, S and R to indicate left, stop and right, current being supplied to these wires from a connection (not shown) with the electric plant of the 20 automobile. These buttons are preferably mounted on a plate 35 which may be secured to an instrument board by screws 36 as desired.

In operating the device it is merely necessary, whenever the driver is about to turn to either side or stop, to press the appropriate button whereupon one of the compartments of the lamp casing will be illuminated and the light will shine through the 30 proper opening in the cover, green lights being used for the arrows and a red light for the "stop" indication in order to better distinguish the same.

There has thus been provided a simple 35 and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed. For instance, it 40 will be noted that two lights may be provided in each compartment to more evenly distribute the lights and also that transparent material, either colored or plain, such as, glass, isinglass, or the like may be used 45 behind the openings.

Having thus described the invention, what is claimed as new, is:—

1. In a signal device, a lamp supporting frame consisting of upper, lower and intermediate members formed each from a single 55 strip of sheet metal and all of uniform width throughout, the upper and lower members being alike but invertedly positioned, said upper and lower members each consisting of a straight body portion, a portion bent at right angles to the body portion whereby to form a broad U-shaped structure and a terminal portion bent at right angles to one of the legs of the U and away from the other leg, the legs of the 60 U in the upper member extending upward and in the lower member extending downward, said intermediate portion being also bent to form a U-shaped structure and having its respective legs secured to the respective 65 body portions of the upper and lower members.

2. In a signal device, a lamp supporting frame consisting of upper, lower and intermediate members formed each from a single 75 strip of sheet metal and all of uniform width throughout, the upper and lower members being alike but invertedly positioned, said upper and lower members each consisting of a straight body portion, a portion bent at right angles to the body portion whereby to form a broad U-shaped structure and a terminal portion bent at right angles to one of the legs of the U and away from the other leg, the legs of the U 80 in the upper member extending upward and in the lower member extending downward, said intermediate portion being also bent to form a U-shaped structure and having its respective legs secured to the respective body portions of the upper and lower members, a casing surrounding said frame and fitting closely to the sides thereof whereby the frame divides the casing into compartments, said casing having one wall provided 85 with apertures affording signal indicia, and lamps each supported on a vertical portion 90 of a respective frame member.

In testimony whereof I affix my signature.
ROY V. LEAF.
